MELVIN L. SEVERY, OF ARLINGTON HEIGHTS, MASSACHUSETTS, ASSIGNOR TO SEVERY MANUFACTURING COMPANY, OF BOSTON, MASSACHUSETTS, A CORPORATION OF MASSACHUSETTS.

EXPANSIBLE PULLEY.

1,132,125.

Specification of Letters Patent. Patented Mar. 16, 1915.

Application filed July 8, 1913. Serial No. 777,872.

To all whom it may concern:

Be it known that I, MELVIN L. SEVERY, of Arlington Heights, in the county of Middlesex and State of Massachusetts, have invented certain new and useful Improvements in Expansible Pulleys, of which the following is a specification.

This invention relates to an improvement in expansible pulleys.

10 The object of the invention is to provide an expansible pulley which is composed of parts that can be readily produced by die casting and are readily assembled, and which can be used in coacting pairs controlled by 15 a single movement.

The invention will be clearly understood from an inspection of the accompanying drawings, in which—

Figure 1 is a plan view showing a pair of 20 pulleys arranged for coaction, together with the means for controlling them, Fig. 2 is a face view of one of the pulleys, showing the upper half of the inner plate removed, Fig. 3 is a fragmentary central vertical section through one end of a pulley, Fig. 4 is a plan view of the pulley partly 25 expanded, Fig. 5 is a face view, on an enlarged scale, of one of the ball-carriers, Fig. 6 is a section taken on the line 6—6 in Fig. 30 5, Fig. 7 is a section taken on the line 7—7 in Fig. 5, Fig. 8 is a section taken on the line 8—8 in Fig. 4, Fig. 9 is a sectional detail view of a portion of the upper end of two adjacent ball-carriers.

35 As illustrated in the drawings, the preferred embodiment of the pulley comprises a pair of flanges, each composed of an inner plate 10, having an outer flat face provided with radial slits 12 through which projections 40 14 extend, said projections being formed on bars 16, which extend between said flanges and form the movable vanes or sections of the pulley. Each vane comprises a dentated peripheral member 18, which may 45 be formed integral with the bar 16, or affixed thereto by screws 20. The dentations of the vanes intermesh in such a manner that when said vanes are in their innermost position they form a substantially continuous peripheral surface, and when they are in their outermost position the edges of the teeth are practically in line or separated slightly, so 50 that there is little or no continuous break in the periphery of the pulley. Thus the periphery of the pulley is formed with small

apertures and a good traction surface is provided over which a slotted belt may be most advantageously used, as this belt is exceedingly flexible and therefore readily conforms to the surface of the pulley, and for 60 the further reason that this form of pulley does not require a belt to engage it so as to form a suction with its periphery.

The projections 14 are formed with reduced ends 22, which project into grooves 24 65 formed in plates or ball-carriers 26. These plates are triangular, as shown in Fig. 5, said plates being preferably attached to the rear faces of the plates 10. The rear faces of the plates 10 are irregular to fit the plates 26, the latter being located diagonally and having the grooves 24 extend in a triangular path to form race-ways for endless series of balls 28, the projections 22 being adapted 70 to enter between two of the balls and be engaged thereby to vary the positions of the vanes 18, when the diameter of the pulley is changed. The plates 26 may be held in place upon the plates 10 by means of screws 30, which pass through the plates 26 into the plates 10, and when said plates 26 are in place their ball-races are closed except where they communicate with the radial slots 12 and the peripheral slots 36.

Surrounding the plates 10 and 26 is a 85 cover-plate 32, having a series of inwardly projecting teeth 34, said teeth being inclined like the plates 26 and adapted to enter the ball-races 24 through slots 36 formed in the tops of the plates 26. The cover plate 32 90 may be made in sections with integral teeth to facilitate the work of assembling. The teeth 34 pass between two balls 28 and operate to push the same around the race-ways when the cover-plate 32 is given a rotary 95 motion. A coiled spring 29 may be interposed in the ball circuit to take up slack and prevent rattling. Where the ball runways communicate with the slots 12 and 36 the former are made shallower than 100 throughout the remainder by the amount which these openings allow the ball surface to protrude. This is shown in Fig. 7 and is to prevent the balls from staggering at these points and thus crowding one another 105 instead of having a continuous line of contact through their centers. Each of the triangular plates 26 is formed with a ledge 27 at its upper rear edge (see Fig. 9), which projects into the recess formed in the next 110

plate, said ledge forming one wall of the peripheral slot 36 in which the tooth 34 travels.

The cover plate 32 is formed with one end wall 38 having a boss 40 within which a sleeve 42 is adapted to slide, said boss and wall being provided interiorly with a pair of circular channels having endless series of balls 44, said balls being arranged to engage a diagonally extending spline 46 on said sleeve. The sleeve 42 extends across the width of the pulley and is provided at its other end with a diagonally extending spline 46, which engages a grooved boss 50 on a cover-plate 52 forming the corresponding end of the pulley.

The pulleys are adapted to be used in co-acting pairs, as shown in Fig. 1, in which the pulleys 60, 61 are mounted on shafts 62, 64 journaled in suitable bearings 66, 67. Upon the shafts 62, 64 are slidably mounted the sleeves 42, 42^a, having grooved collars 68, 68^a, and held against relative rotation with their shafts by splines 70. A lever 72 is fulcrumed at 74 and provided with a handle 76 for operation. The lever 72 is provided with means at its ends for engaging the grooved collars 68, 68^a, so that the sleeves 42 and 42^a may be moved longitudinally with respect to their shafts to adjust the diameters of the pulleys 60, 61. This lever is also provided with a detent 77, which cooperates with a sector 79 to hold said lever locked. When the sleeve 42 is pushed longitudinally into the pulley 60, the sleeve 42^a is withdrawn from the pulley 61, so that when the former is expanded the latter is contracted, and vice versa. When the sleeve 42, for example, is pushed inward the cover-plate 32 is given a partial rotation counterclockwise, and the teeth 34 are moved outward in the slots 36 thus moving the balls 28 toward the right (as viewed in Fig. 5) and the projections 22 on the vanes upward to increase the diameter of the pulley. It will be noted that the pitch of the splines 46 and 48 is very gradual, so that there is no tendency of the belt to cause the pulley to contract by rotating the heads or flanges of the pulley on the sleeve 42, and the detent 77 holds the adjusting lever locked.

What I claim is:—

1. An expandible pulley, comprising a pair of disks having slots, a plurality of ball-carriers mounted on said disks and each provided with an endless series of balls, a plurality of movable sections guided in said slots and engaging said balls, and a member rotatable relatively to said plate and having means for engaging said balls, whereby upon the relative rotation of said members said sections are moved.

2. In an expandible pulley the combination of a shaft, a pulley frame mounted thereon; a plurality of rim sections mounted

in said frame and movable therein to vary their radial distance from said shaft; a plurality of endless ball races corresponding to said rim sections and mounted in said frame; a plurality of endless series of balls 70 confined in said races and operatively engaging corresponding rim sections to move the latter when said ball series are moved; and means for simultaneously moving the series of balls in said races to move said rim 75 sections simultaneously.

3. In an expandible pulley, the combination of a shaft; a pulley frame mounted thereon; a plurality of rim sections mounted in said frame and movable therein to vary their radial distance from said shaft; a plurality of endless ball races corresponding to said rim sections, mounted in said frame; a plurality of endless series of balls movable in said races and in operative engagement with said rim sections to move the same when said series of balls are moved; an actuator rotatably mounted with reference to said frame and shaft, and operatively engaging said series of balls to move the same simultaneously when said actuator is so rotated; and means for rotating said actuator relatively to said frame and shaft.

4. In an expandible pulley, the combination of a shaft; a pulley frame mounted thereon; a plurality of rim sections mounted in said frame and movable therein to vary their radial distance from the shaft; a plurality of endless ball races corresponding to said rim sections mounted in said frame; a plurality of endless series of balls movable in said races in operative engagement with said rim sections to move the same when said series of balls are moved; an actuator rotatably mounted with reference to said frame and shaft and operatively engaging said series of balls to move the same simultaneously when the said actuator is so rotated; and a sleeve axially movable on said shaft and operatively connected with said actuator to rotate the same relatively to said frame and shaft when said sleeve is so moved.

5. In an expandible pulley the combination of a shaft; a pulley frame mounted thereon and provided with substantially radial slots; a plurality of movable rim sections mounted in said frame and having portions extending into and guided by said slots; a plurality of endless ball races one for each of said slots and each having a radial portion parallel to its corresponding slot; a plurality of endless series of balls guided by said races and operatively engaging the portions of the rim sections extending into the aforesaid slots to move said rim sections when said ball series are moved; and an actuator for moving all said ball series in unison.

6. The combination of a shaft; a pulley

frame mounted thereon and provided with radial slots; a plurality of movable rim sections mounted in said frame and having portions projecting into said slots; a plurality of endless ball races one for each of said slots, and each having a radial portion adjacent its corresponding slot; a plurality of endless series of balls guided by said races, each series operatively engaging a portion of a rim section guided by the corresponding slot to move said rim section when said ball series is moved; and an actuating device rotatably mounted with reference to said frame and shaft and engaging said ball series to move the same in unison when said actuator is so rotated.

7. The combination of a shaft; a pulley frame mounted thereon and provided with radial slots; a plurality of movable rim sections mounted in said frame and having portions projecting into said slots; a plu-

rality of endless ball races one for each of said slots, and each having a radial portion adjacent its corresponding slot; a plurality of endless series of balls guided by said races each series operatively engaging a portion of a rim section guided by the corresponding slot to move said rim section when said ball series is moved; an actuator rotatably mounted with reference to said frame and shaft and engaging said ball series to move the same in unison when said actuator is so rotated; and a sleeve axially movable with reference to said shaft and operatively connected to said actuator to rotate the same by the axial movement of said sleeve.

In testimony whereof I have affixed my signature in the presence of two witnesses.
